DESIGN FOR A MUSIC CABINET

Herman Batlin, New York, N. Y.

Application June 18, 1945, Serial No. 120,183

Term of patent 3½ years

(Cl. D56—4)

To all whom it may concern:

Be it known that I, Herman Batlin, a citizen of the United States of America, residing at New York, in the county and State of New York, have invented a new, original, and ornamental Design for Music Cabinet, of which the following is a specification, reference being made to the accompanying drawing, forming a part thereof.

Fig. 1 is a front elevational view of a music cabinet showing my new design; and

Fig. 2 is an end elevational view thereof.
Both ends of the cabinet are the same and the top surfaces thereof are plain.

I claim:

The ornamental design for a music cabinet, substantially as shown and described.

HERMAN BATLIN.
